5 Claims. (Cl. 118—63)

ABSTRACT OF THE DISCLOSURE

A paper web coating mechanism employing an air knife wherein the air jet engages an adjustable deflector plate having a downwardly facing surface and interposed between the air jet and paper web.

The present invention relates to improvements in mechanism for coating travelling webs and more particularly to an improved air knife coater for coating a paper web.

The invention provides a coating mechanism including a backing roll supporting a travelling web with coating applying means applying a coating to the exposed surface of the web and an air knife for smoothing and removing excess coating including an air jet directed toward the surface of the oncoming travelling web on the uprunning side of the backing roll and a deflector plate having a downwardly facing surface interposed in the stream of air from the jet deflecting the air downwardly and at an increased angle toward the oncoming coated web surface with the angle of the plate being adjustable.

An object of the invention is to provide an improved air knife coater with a mechanism for reducing the coating spray at the outgoing side of the knife and reducing or eliminating the need for coating spray collecting apparatus and reducing the inherent disadvantages of residual coating spray which travels in the air and covers adjacent machinery parts.

A further object of the invention is to provide an improved air knife coater wherein the air knife lips stay cleaner and operate at continued optimum performance.

A still further object of the invention is to provide an air knife coater wherein the air flow direction can be changed without requiring adjustment of the air knife.

A still further object of the invention is to provide an air knife coater which can be operated at a fixed distance from the backing roll and travelling web and wherein there is less danger of damaging the air knife.

Yet another object of the invention is to provide an air knife coater which is easier to clean and keep clean.

Other objects, advantages and features will become more apparent with the teaching of the principles of the present invention in connection with the disclosure of the preferred embodiments thereof in the specification, claims and drawings, in which:

The figure of the drawing illustrates schematically a coating mechanism embodying an air knife coater constructed and operating in accordance with the principles of the present invention.

A travelling paper web W moves into the coating mechanism at a constant speed and coating is applied to its lower surface by a coating applicator roll 11. The coating applicator roll runs partially submerged in a coating pan 12 to carry a layer of coating up against the lower surface of the web W. As will be appreciated by those versed in the art coating may be applied to the web by various means.

The coated web travels onto a backing roll 10 and on the uprunning side of the roll is positioned an air knife including an air jet 13 directing a stream of air 14 against the coated surface of the web. In accordance with known operation of air knife coaters, the stream of high velocity air engages the coated surface of the web removing ex-

2

cess coating and smoothing the coating which passes onwardly with the travelling web W.

The removed excess coating runs downwardly into a save-all pan 17 and is carried away and may be transferred back to the main coating pan 12.

In air jet coating because of the velocity of the travelling web and the high velocity of the stream of air, with the coating tending to be thrown centrifugally outwardly, a spray or mist of coating normally develops on the outgoing side of the nozzle 13 of the air knife. Various means have been attempted to reduce this mist including devices for collecting and filtering the mist from the air. This mist will also tend to coat the air knife surfaces and the lips or edges of the knife or nozzle 13 will tend to become coated from coating being thrown outwardly.

In accordance with the present invention means are provided for being interposed in the air stream 14 and deflecting the stream downwardly. A deflector plate 15 is mounted above the air knife nozzle 13 with its free edge 20 extending into the air stream 14 and with its lower surface deflecting the air stream downwardly at an increased angle with respect to the oncoming surface of the web W. This lower surface of the plate 15 changes the angle of the air jet and its effect with respect to the oncoming web 25 surface, and air flow after it engages or impinges the web must flow downwardly after contact. This reduces the mist caused by the air currents which normally form by escaping air and prevents the travelling of a mist upwardly onto the freshly finished coated surface of the web 30 after it passes the air jet thereby improving the quality of the coating on the paper surface. The fine particles of mist which normally escape become partially dried while travelling in the air and when they engage on the surface of the finished coated web they do not melt or merge into 35 the surface but provide surface imperfection. This is eliminated with the present arrangement.

In operation coating is applied to the undersurface of the travelling web W and the air jet from the air nozzle 13 as deflected by the overhead plate 15 engages the 40 freshly coated surface removing the excess coating to run down into the save-all pan 17 and the finished coated surface continues on with the web W. For optimum operation adjustment of the deflector plate 15 is possible such as by provision of an adjustment screw 16 mounted at 45 the top of the nozzle. This can be used as a partial support for the deflector 15. If desired additional adjustment means can be provided for adjusting the position of the plate 15 parallel to its plane and toward or away from the surface 50 of the travelling web W.

This adjustment mechanism can be provided by various means such as adjustment screws which need not be shown in detail, but instead are illustrated schematically by the arrowed line 18.

With the arrangement shown the nozzle 13 can be 55 kept a substantial distance from the travelling web W and adjustment of the direction of the air flow can be made without adjustment of the jet reducing the danger of damaging the air knife during adjustment or installation.

Thus it will be seen that I have provided an improved 60 coating arrangement and method which meet the objectives and advantages above set forth. The structure is relatively simple in operation and construction and can be 65 utilized in existing coaters or in new coaters with a minimum of expense and space requirement.

The drawings and specification present a detailed disclosure of the preferred embodiments of the invention, and it is to be understood that the invention is not limited 70 to the specific forms disclosed, but covers all modifications, changes and alternative constructions and methods

falling within the scope of the principles taught by the invention.

I claim as my invention:

1. A coating mechanism comprising in combination, a backing roll supporting a travelling web, coating applying means applying coating to the surface of the web, 5

an air knife for smoothing and removing excess coating including a primary coating smoothing air jet directed toward the surface of the travelling web on 10

the backing roll, a deflector plate having a surface interposed in the stream of air from the jet deflecting the air toward the oncoming coated web surface, and means for adjusting the angle of said plate relative to said jet. 15

2. A coating mechanism comprising in combination, a backing roll supporting a travelling web, coating applying means applying coating to the surface of the web, 20

an air knife for smoothing and removing excess coating including a primary coating smoothing an air jet directed toward the surface of the travelling web on the backing roll,

and a deflector member having a surface interposed in the stream of air from the jet deflecting the air toward 25 the oncoming coated web surface.

3. In combination with a coating mechanism having means for applying a layer of coating to the surface of a continuously travelling web,

a primary coating smoothing air knife coater having an 30 air jet directing a stream of air against the coated surface, and means deflectively engaging the air stream between the web and jet and changing the direction of the stream of air relative to the web. 35

4. A coating mechanism comprising in combination, a backing roll having a surface supporting a travelling web,

coating applying means applying coating to the surface of the web,

an air knife for smoothing and removing excess coating including a primary coating smoothing air jet directed toward the surface of the travelling web on the uprunning side of the roll,

a deflector plate mounted above said air jet having an edge projecting beyond the jet with a downwardly facing surface projecting into the air stream and deflecting air downwardly, and means on the knife for adjustably changing the angle of the plate relative to the jet.

5. A coating mechanism comprising in combination, a backing roll having an outer cylindrical surface for supporting a travelling paper web,

a coating applicator roll positioned in advance of the backing roll for applying a layer of coating to the exposed surface of the web, a coating pan positioned with the coating roll partially submerged therein for carrying coating onto the web surface,

a primary coating smoothing air jet positioned on the uprunning side of the backing roll directing a stream of air onto the coated surface of the web and directed at an angle with respect to the web toward the oncoming web for removing excess coating and smoothing the remaining coating on the web,

a deflector plate mounted on the air jet having an edge extending beyond the jet with a downwardly facing surface interposed in the stream of air from the jet deflecting the air stream downwardly and directly air flow downwardly after impingement contact with the coated surface of the web, and adjustment means on said air jet for positioning the angle of said plate relative to the air jet.
